United States Patent Office

Des. 185,714
Patented July 21, 1959

185,714

COMBINATION GLASS AND REFERENCE ELECTRODE

John E. Leonard and Hideo Watanabe, Fullerton, Calif.,
assignors to Beckman Instruments, Inc., Fullerton,
Calif., a corporation of California

Application April 25, 1957, Serial No. 45,893

Term of patent 14 years

(Cl. D26—1)

Fig. 2.

Fig. 1 is a side view of a combination glass and reference electrode, showing our new design; and

Fig. 2 is a bottom view thereof.

The dominant features of our design reside in the portions shown in full lines.

We claim:

The ornamental design for a combination glass and reference electrode, substantially as shown and described.
